UNITED STATES PATENT OFFICE.

HARRY C. BUHOUP, OF CHICAGO, ILLINOIS, ASSIGNOR TO THE McCONWAY & TORLEY COMPANY, OF PITTSBURGH, PENNSYLVANIA, A CORPORATION OF PENNSYLVANIA.

CAR-COUPING.

1,201,437.

Specification of Letters Patent. Patented Oct. 17, 1916.

Application filed May 26, 1916. Serial No. 100,106.

To all whom it may concern:

Be it known that I, HARRY C. BUHOUP, a citizen of the United States, residing at Chicago, in the county of Cook and State of Illinois, have invented certain new and useful Improvements in Car-Couplings; and I do hereby declare the following to be a full, clear, and exact description of the invention, such as will enable others skilled in the art 10 to which it appertains to make and use the same.

My invention relates to the construction of car couplers, and has for its object the reinforcement of the coupler stem and the facilitation and simplification of repairs, as well 15 as a reduction of expense where repairs become necessary.

Car couplers, which are in general made of cast metal and of an integral construction, comprise a coupler head, a butt member for connection with the yoke of a draft rigging, and an intermediate stem member which connects the head and butt members.

Owing to the necessarily limited cross sectional area of the coupler stem and to the fact that, in service, the coupler is subjected to violent shocks and great transverse as well as longitudinal strains, it results that the stem of a coupler is frequently broken, which 30 necessitates the scrapping of the coupler as a whole and its total loss.

To overcome the liability of fracture of the stem, as well as to facilitate repairs and to minimize loss, I form the coupler of a plurality of abutting, longitudinally disposed members combined with a spanner member or members of wrought metal, such for instance as rolled steel; and such a construction involves the main feature of my 40 invention.

There are other features of invention, all as will hereinafter more fully appear.

I will now proceed to describe my invention more fully, so that others skilled in the art to which it appertains may apply the same.

In the drawings chosen for the purpose of illustrating my invention, the scope whereof is pointed out in the claims—

Figure 1 is a plan view of a car coupler embodying my invention in its preferred form. Fig. 2 is a side elevation of the coupler shown in Fig. 1. Fig. 3 is a cross section of the stem, taken on the line 3—3, Fig. 52. Fig. 4 is a view in side elevation of the

butt of the coupler and a portion of the stem adjacent thereto, showing a modification involving a reduction in the length of the spanner member of the coupler. Fig. 5 is a cross section of the coupler stem, showing a modified form of spanner member. Fig. 6 is a plan view of a coupler, showing a modified arrangement of the spanner member with relation to the abutting members of the stem. Fig. 7 is a side elevation 65 of the modification shown in Fig. 6. Fig. 8 is a cross section of the modification shown in Figs. 6 and 7, the section being taken on the line 8—8, Fig. 7.

Like symbols refer to like parts wherever 70 they occur.

In the drawings, A indicates the coupler head member, B the coupler butt member, and C the intermediate stem member which connects the head and butt members.

E indicates portions of the yoke member of a draft rigging with which the butt member B of the coupler is connected by a pin inserted through the pin-holes e of the butt member.

The head and butt members, so far as their configurations are intended for effecting connections with coacting structures is concerned, may be of any well known character, but for reasons which will hereinafter appear I prefer to use a quadruple shear butt for connection with the yoke of a draft rigging.

1, 1 indicate the longitudinally disposed abutting stem members of the coupler, with 90 one of which the coupler head A may be integral and with the other of which the butt member B may be integral. These members are preferably of forked form, or centrally slotted, as shown at 2 in Figs. 1 and 2, and in case of a quadruple shear coupler but the slot in the stem portion adjacent thereto is preferably extended into the butt, as indicated in dotted lines at 2^a, Fig. 2 of the drawings, to thus permit the spanner member to reinforce the butt member. But, if desired, the spanner may be a member 3^a which terminates at the point of connection of the stem C and butt B, as indicated at 2^b in Fig. 4. The abutting ends of the stem members 1, 1, are preferably of tongue and groove form, as indicated at 2^c, in order that they may interlock and thus afford a greater conjoint action of the members 1, 1 in resisting lateral strains. In conjunction with 110

the abutting stem members 1, 1, which usually are of cast metal, I employ a spanner member or spanner members of wrought metal, as for instance rolled bars or plates 5 of wrought iron or steel.

In the preferred construction shown in Figs. 1, 2 and 3 of the drawings, where the spanner member is centrally disposed, as at 3, only a single spanner member will be required, and, as before noted, this may be extended into the butt member B, as indicated at 2^a. Also, if desired, this centrally disposed spanner member may be a flanged structural steel shape, as for instance an 15 I-beam, as shown at 3^b in the cross sectional view Fig. 5. In such case the stem members 1, 1 will be recessed longitudinally, as at 1^a to accommodate the flanges of the I-beam, and with such a spanner member the stem 20 will have an added resistance to vertical strains, measurably proportionate to what would result in case the spanner members were arranged with their greatest width set vertically rather than in the preferred horizontal position. 25

While a structure in which the stem members are slotted longitudinally is to be preferred, yet in case the abutting stem members are centrally disposed, as at 5 in Figs. 30 6, 7 and 8 of the drawings, and the spanner members are external thereto, as at 6, the structure may be lightened without loss of strength by coring the abutting stem members, provision being made for rivet thimbles 5^a which serve as cross braces or supporting posts for the hollow stem members 5; and I also prefer to recess or countersink the outer faces of the stem members as at 35 5^b for the reception of the spanner members 6.

The abutting stem members 1 or 5 and the corresponding spanner members 3, 3^a, 3^b or 6, as the case may be, after having been assembled as indicated in the drawings, are 45 finally rigidly secured by a series of rivets or bolts 4, 4 which complete a structure adapted to resist high transverse strains and resultant fractures.

Having thus described my invention, what 50 I claim and desire to secure by Letters Patent is:

1. A car coupler comprising a plurality of abutting stem members, one having a coupler head integral therewith and another having a coupler butt member integral therewith, a spanner member which overlaps the stem members with which the coupler head and butt are integral, and means for rigidly connecting the stem and spanner members.
- 60 2. A car coupler comprising a plurality of longitudinally slotted abutting stem members, one having a coupler head integral

therewith and another having a coupler butt integral therewith, a centrally disposed 65 spanner member which overlaps the stem members with which the coupler head and butt are integral, and means for rigidly connecting the stem and spanner members.

3. A car coupler comprising a plurality 70 of longitudinally and centrally slotted abutting stem members, one having a coupler head integral therewith and another having a coupler butt integral therewith, a centrally disposed spanner member which overlaps the abutting stem members and extends into the coupler butt member, and means for rigidly connecting the stem and spanner members. 75

4. A car coupler comprising a plurality 80 of abutting stem members having interlocking abutting faces, one of said stem members having a coupler head integral therewith and another having a coupler butt integral therewith, a spanner member which overlaps the stem members, and means for rigidly connecting the stem and spanner members. 85

5. A car coupler comprising a plurality 90 of abutting stem members, one of said stem members having a coupler head integral therewith and another having a coupler butt integral therewith, a wrought metal spanner member which overlaps the abutting stem members, and means for rigidly connecting the stem and spanner members. 95

6. A car coupler comprising a plurality 100 of cast metal abutting stem members, one of said stem members having a coupler head integral therewith and another having a butt member integral therewith, a wrought metal spanner member which overlaps the abutting stem members, and means for rigidly connecting the stem and spanner members. 105

7. A car coupler involving a plurality of 110 stem members, one having a coupler head integral therewith, one having a coupler butt integral therewith, and one whose length exceeds that of the first noted members, said last named member being of wrought metal, the first-named members being arranged to abut and the last-named member being arranged to overlap the abutting members, and means for rigidly connecting the several 115 members comprising the stem.

8. A car coupler stem comprised of a plurality of longitudinally aligned transversely abutting members, a spanner member arranged in parallel relation with and overlapping the abutting members, and means for rigidly connecting the several members which comprise the coupler stem. 120

In testimony whereof I affix my signature.

HARRY C. BUHOUP.
